US00D993092S

(12) **United States Design Patent** (10) **Patent No.:** **US D993,092 S**
Kermani (45) **Date of Patent:** **** Jul. 25, 2023**

(54) **DRIFTING KART**(71) Applicant: **Ali Kermani**, Huntington Beach, CA (US)(72) Inventor: **Ali Kermani**, Huntington Beach, CA (US)(73) Assignee: **Razor USA LLC**, Cerritos, CA (US)(***) Term: **15 Years**(21) Appl. No.: **29/841,218**(22) Filed: **Jun. 3, 2022****Related U.S. Application Data**

(63) Continuation of application No. 29/772,302, filed on Mar. 1, 2021, now Pat. No. Des. 953,938, which is a continuation of application No. 29/698,468, filed on Jul. 17, 2019, now Pat. No. Des. 913,165, which is a continuation of application No. 29/612,530, filed on Aug. 1, 2017, now Pat. No. Des. 854,458, which is a continuation of application No. 29/564,412, filed on May 12, 2016, now Pat. No. Des. 793,912, which is a continuation of application No. 29/474,831, filed on May 9, 2014, now abandoned.

(57) CLAIM

The ornamental design for a drifting kart, as shown and described.

DESCRIPTION

FIG. 1 is a top, front, and right side perspective view of a drifting kart showing my new design;

FIG. 2 is a top, rear, and left side perspective view thereof;

FIG. 3 is a top plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines in the drawings illustrate portions of the drifting kart that form no part of the claimed design.
